UNITED STATES PATENT OFFICE

1,937,119

PRINTING MACHINE

Curtis George Kranz, Chicago, Ill., assignor to
Addressograph Company, Chicago, Ill., a cor-
poration of Delaware

Original application November 1, 1929, Serial No.
404,092. Divided and this application Febru-
ary 6, 1931. Serial No. 513,947

8 Claims. (Cl. 101—415.1)

This application is a division of my applica-
tion, Serial No. 404,092, filed November 1, 1929.

This invention relates to printing machines and
more particularly to an impression or platen cyl-
5 inder for a printing couple. The salient objects
of my invention are to provide a platen or im-
pression cylinder on which a blanket may be
mounted and to which one end of the blanket
may be tightly secured; to provide for tightening
10 the blanket in order that it may be arranged in
taut condition; and to provide an impression
cylinder with which a make-ready may be used
when required.

In the selected embodiment of my invention
15 illustrated in the accompanying drawing

Fig. 1 is a side view of my improved impression
cylinder;

Fig. 2 is a sectional detail view; and

Fig. 3 is a sectional detail taken substantially
20 on the line 3—3 on Fig. 2.

In the accompanying drawing I have illus-
trated my improved impression cylinder as used in a
printing couple in connection with a printing
cylinder of the character described and claimed
25 in my co-pending application, Serial No. 511,707,
filed January 28, 1931, and such a printing couple
is used in connection with a printing machine of
the kind described and claimed in the applica-
tion from which this application has been divided.

30 The printing cylinder and the platen or im-
pression cylinder of this invention will preferably
be operated in synchronism. The impression cyl-
inder is indicated by 4 and is suitably mounted
on a shaft 5 to be rotatable therewith. On the
35 periphery of the cylinder is a wide flange 6 in-
cluding an enlarged portion 7 and a formed por-
tion 8 which are arranged in spaced relation to
define therebetween a recess 9. The formed por-
tion 8 provides an outwardly opening recess 10
40 having an inclined edge 11. A wedge block 12
includes an inclined edge 13 adapted to coop-
erate with the inclined edge 11 when one end of
a cushion blanket 14 arranged on the periphery
of the flange 6 is disposed between the wall of
45 the recess 10 and the edge of the block 12 op-
posite the inclined edge 13. Screws 15 pass free-
ly through the block 12 and into the formed por-
tion 8 and by tightening these screws the block
12 may be moved inwardly and by reason of the
50 cooperation of the inclined edges 11 and 13 the
end of the blanket will be tightly secured to pre-
vent displacement thereof. The blanket 14 is
directed around the periphery of the flange 6 and
the free end thereof is extended into the recess
55 9. In the recess 9 is a block 16 having a projec-

tion 17 on one face thereof and the end of the
blanket 14 is directed over this face into engage-
ment with the shoulder defined by the projection
17. Another block 18 is then rested on the blanket
and the screws 19 are freely passed through the
block 18 and the blanket and into the block 16
60 to thereby securely clamp this end of the blanket
to the block. At opposite ends of the block 18,
ears 20 are formed and on the face of the formed
portion 8, providing a wall of the recess 9, grooves
65 21 are formed at the outer edges in which the
ears 20 are disposed, and the cooperating engage-
ment of these ears with the grooves 21 prevent
endwise movement of the block 18 and conse-
quently the block 16 which is secured thereto, and
70 in this manner this end of the blanket is secured
and properly positioned on the periphery of the
flange 6. On the face of the block 16, opposite
that having the end of the blanket disposed there-
on, a rack 22 is provided. In the enlarged portion
75 7 is an opening 23 in which an elongated pinion
24 is passed and the teeth of this pinion mesh
with the teeth of the rack 22. A groove is formed
in the periphery of the pinion 24 and a pin 26
is passed through this groove to thereby prevent
80 axial displacement of the pinion 24 from the
opening 23. At one end of the pinion 24, a ratchet
27 is formed of substantially the same diameter
as the pinion and this ratchet is arranged to
partially extend into the opening 23 and is se-
85 cured to the pinion 24 by being pinned, as indi-
cated at 28, or in any other suitable manner. At
one end of the pinion 24 a tool grip 29 is provided
and by connecting a suitable tool to this tool grip
the pinion 24 may be rotated and when turned
90 in a clockwise direction this pinion will act on the
rack 22 to move the blocks 16 and 18 inwardly to
thereby tension the blanket 14. A pawl 30 piv-
tally mounted at 31 is acted on by a spring 32 and
normally engages the teeth of the ratchet 27, and
95 this prevents unloosening movement to thereby
retain the rack 22 in any position into which it
is moved by manipulation of the pinion 24. Mani-
festly, a make-ready may be easily associated with
the blanket by merely moving the pawl 30 from
100 engagement with the ratchet 27 after which the
blocks 16 and 18 may be moved from the recess 9,
and after the make-ready has been arranged in
position the blocks will again be passed into the re-
cess and the rack 22 meshed with the pinion 24 105
after which the pinion will be turned in the man-
ner described to again bring the blanket into taut
condition on the periphery of the flange 6. In
order that access may also be had to the pawl
30 and the end of the pinion 24 having the tool
110

grip 29 thereon, I lock the cylinder 4 to the shaft 5 by a dog 33 mounted on the hub of the cylinder and engaging a recess in the collar 34 fixed to the shaft. The dog may be manually operated to 5 release the cylinder from the shaft so that it can be turned into any desired position for adjusting or replacing the blanket. However, since connection will be made to the shaft by the dog 33 engaging the recess in the collar 34 it is manifest 10 that the relation between the platen cylinder and the printing cylinder may be maintained and thus proper synchronic operation thereof may be brought about.

While I have illustrated and described a selected 15 embodiment of my invention, it is to be understood that this is capable of variation and modification and I do not wish to be limited to the precise details set forth but desire to avail myself of such changes and alterations as fall within 20 the purview of the following claims:

I claim:

1. In a printing machine, a platen cylinder having a recess therein, a cushion blanket, means securing one end of said blanket to said cylinder, 25 clamp means securing the other end of said blanket and disposed in said recess, a rack on said clamp means, and a pinion meshed with said rack and rotatable to move said clamp means through said recess to tighten said blanket on 30 said cylinder.

2. In a printing machine, a platen cylinder having a recess therein, a cushion blanket, means securing one end of said blanket to the cylinder, clamp means secured to the other end of the 35 blanket and disposed in said recess, a rack, a pinion meshed with said rack and rotatable to move said clamp means through said recess to tighten said blanket on said cylinder, and releasable means holding said pinion against rotation 40 to hold said blanket tight on said cylinder.

3. In a printing machine, a platen cylinder having a recess therein, a cushion blanket, means securing one end of said blanket to the cylinder, clamp means secured to the other end of said 45 blanket and disposed in said recess, a rack on said clamp means, and a pinion rotatably mounted in said cylinder and meshed with said rack and rotatable to move said clamp means through said recess to tighten said blanket on said cylinder.

4. In a printing machine, a platen cylinder having a recess therein, a cushion blanket, means securing one end of said blanket to the cylinder, clamp means secured to the other end of said 55 blanket and disposed in said recess, a rack on said clamp means, a pinion rotatably mounted in

said cylinder and meshed with said rack to move said clamp means through said recess to tighten said blanket on said cylinder, and means for holding said pinion against unloosening movement.

5. In a printing machine, a platen cylinder having a recess therein, a cushion blanket, means securing one end of said blanket to the cylinder, clamp means secured to the other end of said blanket and disposed in said recess, a rack on said clamp means, a pinion rotatably mounted in said cylinder and meshed with said rack to move said clamp means through said recess to tighten said blanket on said cylinder, a ratchet connected to said pinion, a pawl engaged with said ratchet to hold said pinion against unloosening movement, and means urging said pawl into holding position.

6. In a printing machine, a platen cylinder having a formed portion providing a pocket having an inclined edge, a cushion blanket having one end thereof extended into said pocket, a block having an inclined tapered edge adapted for co-operation with said inclined edge, means for securing said block in said pocket with the tapered edge thereon in engagement with the tapered edge of the pocket to clamp said end of the blanket between said block and the wall of the pocket opposite said inclined edge to thereby secure said end of said blanket to the cylinder, and means for adjustably securing the other end of said blanket to the cylinder to vary the tension of said blanket on said cylinder.

7. In a printing machine which has a platen cylinder, a cushion blanket on said cylinder, and means on the cylinder for tightening the blanket thereon, the combination therewith of a shaft, a releasable locking member, and means engageable in the locking member for connecting the cylinder to the shaft, said locking means being released to permit the cylinder to be turned to a convenient position for manipulating said tightening means.

8. In a printing machine which has a platen cylinder, a cushion blanket on said cylinder, and means on the cylinder for tightening the blanket thereon, the combination therewith of a shaft, a releasable locking member on the cylinder, means on the shaft engageable by the locking member to connect the cylinder to the shaft, and means urging the releasable locking member into engagement with the means on the shaft to be engaged thereby, said locking member being released to permit the cylinder to be turned to a convenient position for manipulating said tightening means.

CURTIS GEORGE KRANZ.
